CLAIM

The ornamental design for a cover for a casket, as shown and described.

DESCRIPTION

FIG. 1 is a top front perspective view of a cover for a casket showing my new design.

FIG. 2 is a bottom front perspective view thereof;

FIG. 3 is a top plan view thereof;

FIG. 4 is a bottom plan view thereof;

FIG. 5 is a left side elevation view thereof, the right side elevation view being a mirror image; and,

FIG. 6 is a front side elevation view thereof, the back side elevation view being a mirror image.

1 Claim, 5 Drawing Sheets(56)
